UNITED STATES PATENT OFFICE.

JULIAN H. KENDIG, OF PITTSBURGH, PENNSYLVANIA, ASSIGNOR TO BUDA COMPANY,
OF CHICAGO, ILLINOIS, A CORPORATION OF ILLINOIS.

SWITCH-LATCH.

1,087,297.

Specification of Letters Patent. Patented Feb. 17, 1914.

Application filed May 29, 1913. Serial No. 770,673.

To all whom it may concern:

Be it known that I, JULIAN H. KENDIG, a citizen of the United States, and residing at Pittsburgh, in the county of Allegheny and State of Pennsylvania, have invented 5 certain new and useful Improvements in Switch-Latches, of which the following is a specification, reference being had to the accompanying drawings.

10 This invention relates in general to switch latches, and more particularly to that type of switch latch, wherein the throwing lever of the switch is held in position against ordinary train movement, but which yields under certain conditions, such as for example 15 when a train runs through the switch, thereby preventing a derailment or breakage of switch parts.

The principal object of the invention is to 20 provide a novel switch latch adapted to positively hold the throwing lever of the switch in position against this ordinary train movement, and further adapted to permit the lever to be thrown by the hand, and to permit 25 the automatic release thereof under abnormal pressure; another object is the provision of a simple and inexpensive arrangement of latching mechanism which is positive and effective in operation; and a further 30 object is the provision of means in a switch latch whereby it is intended to provide a latch proper which does not project into the downward path of the throwing lever, thereby eliminating possibility of 35 breakage of the said latch.

These, together with such other objects as may hereinafter appear, or are incident to my invention, I attain by means of a construction illustrated in preferred form in 40 the accompanying drawings, wherein:—

Figures 1 and 2 represent an assembled side elevation and a plan view respectively, illustrating the relation of the switch latch to the rest of the switch mechanism;

45 Figures 3 and 4 are vertical sectional views of the latch itself, and taken from the right and left of Figures 1 and 2 respectively; Figure 3 showing the latch proper in normal and retracted position, 50 with Figure 4 illustrating the latch in operative and advanced position.

55 Referring first to the general arrangement of parts as shown in Figures 1 and 2, the numeral 5 indicates a switch stand of conventional type, provided with the usual

throwing or operating lever 6 carrying the weight 7 at its free end, and designed to actuate the crank arm 8 which leads to the switch. The latches, wherein my invention particularly resides, are represented by the 60 numeral 9—9, and are suitably positioned adjacent each side of the stand 5.

Referring now more particularly to the latch as illustrated in Figures 3 and 4, I provide a casing 10 having a base 11, and further provided with a socket portion 12 forming a yoke 13, into which the lever 6 is adapted to be received when thrown over to set the switch for main or branch line positions.

70 Within the casing 10 is the latch 14 which is pivoted as indicated at 15; and a spring 16 which is suitably mounted to have one of its ends take against the wall of the casing and the other against the free end of the 75 latch. The action of the spring 16 then is to force the nose 14a of the latch 14 toward and to project into the socket 12.

In the practice of my invention, I have 80 found it very effective to have the latch normally held away from and out of the path of the downward movement of the lever, thus affording no obstruction to the free passage of the lever into the socket, which latter forms the limit of this movement. To accomplish this I provide a novel tripping mechanism adapted to normally hold the latch in retracted position, and which on being released therefrom permits the latch to exercise its function of holding the lever 85 against ordinary train movement, and at the same time is adapted to allow the automatic release of the lever when subjected to abnormal pressure.

The tripping mechanism referred to comprises a pawl 17 pivoted at one end in the casing, and provided with a shoulder 17b which is designed to normally engage a stop 14b formed on the latch 14 at a point substantially below its pivot. The pawl further has an extension 17c which, when the pawl co-acts with the latch to hold it in retracted position, projects upwardly through the base of the socket to lie in the downward path of the lever. The engagement 1 between these co-acting members is obtained through the pressure of the light coil spring 18, which is interposed between the base of the casing and the free end of the pawl, as will be seen on an inspection of the drawings. 1

The operation of the device is substantially as follows: In the form of construction as shown and with the latch in retracted position as in Figure 3, the operating lever 5 on being thrown to set the switch describes an arc about its pivotal point, and when descending freely enters the socket 12, and at substantially the end of this movement trips the pawl, forcing it downwardly 10 against the pressure of the spring 18 and releasing the latch, whose nose then moves to advanced or closed position through the action of the spring 16, where it projects into the socket and bears down upon the lever in 15 the manner indicated in Figure 4. It will be apparent that when the pawl is thus in its turn retracted, it takes up another position where it abuts the latch, rendering the spring 18 inoperative to exert any upward 20 pressure on the lever.

When the throwing lever is swung up, it forces the latch inwardly against the pressure of the upper spring 16, and as the lever rises in the socket the pawl 17 moves upwardly to engage the stop 14^b and holds the latch 14 in retracted position, and out of the path of the lever.

If desired, for convenience in the manual operation of the lever, the latch may be 30 retracted by pressing down upon the lever 19 which projects outwardly from the casing 10 for that purpose. Instead of having the latch automatically releasable, it may furthermore be made non-automatic by providing an aperture 20 in the casing, into 35 which a padlock—not shown—may be inserted for the purpose of retaining the latch in the position shown in Figure 4. The nose of the latch is preferably under beveled 40 to facilitate the automatic releasing of the lever.

The entire arrangement is simple, and the device may be easily and cheaply manufactured; and all the parts are housed within 45 a single casing which is designed to protect them from being tampered with by mischievous persons. I do not intend to restrict myself to the exact details of construction, nor to the precise arrangement of the parts as 50 shown, as it is obvious that certain structural variations may be made, without departing from the scope and spirit of my invention as clearly pointed out in the appended claims. The essential features, elements 55 and the operation of the device, together with its effectiveness and other advantages thereof, will be readily apparent to those skilled in the art.

What I claim is:

60 1. In an automatic switch mechanism, a throwing lever, a stand adapted to receive the throwing lever, a latch normally held in locking position in the path of the lever but automatically releasing on abnormal pressure on the lever, and a trip mechanism for

holding the latch in retracted position out of the path of the lever, said mechanism being actuated by the lever to release the latch when the lever is thrown into the stand.

2. In automatic switch mechanism, a 70 throwing lever, a latch for locking the lever normally lying in locking position in the path of the lever, means whereby the latch automatically releases upon abnormal pressure on the lever, and a trip mechanism for 75 holding the latch in retracted position out of the path of the lever, said trip mechanism being actuated by the lever to release the latch when the lever has passed the latch a sufficient distance to be locked thereby. 80

3. In automatic switch mechanism, a throwing lever, a latch for locking the lever yieldingly held in locking position in the path of the lever, means whereby the latch automatically releases upon abnormal pressure on the lever, and a trip mechanism holding the latch in interlocking position out of the path of the lever, said trip mechanism being actuated by the lever to release the latch when the lever has moved into position to be locked by the latch. 85

4. In automatic switch mechanism, a throwing lever, a stand adapted to engage the lever, a latch normally held in the path of the lever and automatically releasing on 90 abnormal pressure tending to force the lever out of the stand, and a pawl adapted to engage the latch and hold it in retracted position out of the path of the lever, the said pawl lying in the path of the lever and 95 being actuated thereby to release the latch when the lever has moved into the stand in position to be locked by the latch. 100

5. In automatic switch mechanism, a throwing lever, a stand adapted to receive 105 the lever, a latch mounted in the stand, a spring yieldingly holding the latch in locking position in the path of the lever, a pawl pivoted to the stand and adapted to hold the latch in retracted position out of the path of 110 the lever, and a spring normally holding the pawl in engagement with the latch, the free end of the pawl lying in the path of the lever whereby the movement of the lever into the stand actuates the pawl to release the 115 latch. 120

6. In automatic switch mechanism, a throwing lever, a stand adapted to receive the lever, a latch mounted in the stand, a spring yieldingly holding the latch in locking position in the path of the lever, means whereby the latch automatically releases upon abnormal pressure tending to throw the lever out of the stand, a pawl pivoted to the stand and adapted to hold the latch 125 in retracted position out of the path of the lever, and a spring normally holding the pawl in engagement with the latch, the free end of the pawl lying in the path of the lever whereby the movement of the lever into 13

the stand actuates the pawl to release the latch.

7. In automatic switch mechanism, a throwing lever, a stand adapted to receive the lever, a latch normally preventing throwing of the lever into the stand and automatically releasing upon abnormal pressure on the lever tending to move the lever out of the stand after it has been received thereby, and automatic trip mechanism for holding the latch out of the path of the lever in position to be engaged and actuated by the lever to release the latch when the lever has been moved into the stand.
- 15 8. In a switch stand, a stand for receiving a throwing lever, a locking means adapted to be retracted by the throwing lever upon abnormal pressure on the lever, and

means for holding the locking means in retracted position when the lever is disengaged.

9. In a switch stand, a stand for receiving a throwing lever, a latch means normally retaining the lever in engagement with the stand, and means automatically actuated when the lever is disengaged from the stand to hold the latch means in retracted position out of the downward path of the lever.

In testimony whereof I have hereunto signed my name in the presence of the two 30 subscribed witnesses.

JULIAN H. KENDIG.
